DOOR LATCH

Samuel R. Fraim, Lancaster, Pa., assignor to E. T.
Faim Lock Company, Lancaster, Pa.; a corpora-
tion of Pennsylvania

Application May 6, 1949, Serial No. 91,809

5 Claims. (Cl. 292—66)

1

This invention relates to door latches and more particularly to latches for screen doors, and a principal object of the invention is to provide a latch of this class which shall be relatively strong and rugged and also mechanically uncomplicated so that the cost of production may be relatively low.

Another object of the invention is to provide a latch device of the stated class consisting essentially of three primary parts including a lever structure incorporating both the outside and inside door handles and also a bolt element, a bracket which pivotally supports the lever member and which is adapted to be secured to the door, and a keeper element of simple form adapted to be secured to the door frame for operative engagement with the bolt element carried in the lever structure.

The invention resides also in certain novel structural features and mechanical devices hereinafter described and illustrated in the attached drawings, wherein:

Fig. 1 is a top plan view of a screen door provided with a latch made in accordance with the invention;

Fig. 2 is a transverse sectional view through the door and latch;

Fig. 3 is a view in perspective of the lever and bracket assembly detached from the door;

Fig. 4 is a view in perspective of the bracket element of the lever assembly;

Fig. 5 is a fragmentary front elevational view of the latch in assembly with the door;

Fig. 6 is a fragmentary view in perspective of the mid portion of the handle lever;

Figs. 7 and 8 are, respectively, sectional views on the lines 7—7 and 8—8 of Fig. 1; and

Fig. 9 is an enlarged view of the bolt and keeper showing the forces acting thereon.

With reference to the drawings, the latch comprises the following elements: a latch actuating lever 1 which comprises an outer handle 2 and an inner handle 3, the lever and handles being made in the present instance of one integral piece; a bracket element 4 to which the lever 1 is pivotally connected by means of a pin 5 and which is attached to the inner face of the door 6 by means of screws 7, see Fig. 5, the exposed portion of the bracket appearing as a plate 8 on the inner face of the door, as illustrated; a keeper element 9 which is secured to the door frame 11, as best shown in Figs. 1, 2 and 5; and a spring pressed bolt 12 which is mounted in the body of the lever 1 and which cooperates with the keeper 9 as hereinafter more specifically described to latch the door.

2

With reference more particularly to Figs. 2 and 3, the lever 1, in assembly, extends through a transverse opening 13 in the door 6; this opening being circular in form, as indicated by broken lines in Fig. 8. The bracket element 4 overlies the inner end of the opening 13 and has within itself an elongated opening 10 through which the lever passes. The bracket has also a pair of spaced ears 14 and 15 which project into the opening 13 and between which the lever 1 is pivotally supported. The lever 1 has at its mid-section a pair of spaced projecting ears 16 and 17 which in assembly and as shown in Fig. 3 occupy positions at the inner faces of the ears 14 and 15 of the bracket member 4, the ears 14, 15, 16 and 17 having registering apertures for reception of the pivot pin 5 which connects the lever with the bracket. In order to properly locate the bracket on the door a pair of projecting teats 18 is provided on the inner surface of the plate 8 arranged to engage the cylindrical wall of the opening 13, these teats being so placed with respect to the ears 14 and 15 that when the ears engage one side of the opening, see Fig. 2, the teats will engage the opposite side.

As best shown in Fig. 2, a coil spring 19 is supported on the pin 5 between the ears 16 and 17 of the lever, one end 21 of this spring seating against a surface 22 of the bracket 4 and the other end 23 of the spring extending into a transverse slot 24 in the upper side of the lever 1 and seating against one wall 25 of this recess. The spring 19 being under tension exerts pressure tending to turn the lever 1 or its pivot in a clockwise direction as viewed in Figs. 1 and 2. The lever may be turned about the pivot 5 in the opposite direction against the pressure of the spring by pulling the handle 2 away from the door or by pressing the handle 3 toward the door.

The outer end of the opening 13 is normally closed by a plate 26 which is secured to the door by screws 27. As shown in Fig. 8 this plate has three teats 28, 29 and 31 projecting from the inner side thereof which are arranged to engage the wall of the opening 13 to thereby locate the plate 26 on the outer face of the door. The plate has an opening 32 through which the lever 1 extends as shown in Fig. 2, this opening being elongated to afford clearance for the aforescribed movements of the lever 1 about the pivot 5. Pivotally supported against the inner face of the plate 26 is an inner plate 33, this plate being pivotally mounted upon the teat 29. The plate 33 has an opening 34 which embraces the portion of the lever 1 which projects therethrough with small clearance, as best shown in Figs. 2 and 8.

The plate 33 has the effect of closing the elongated opening 32 in the plate 26 but being movable on the pivot 29 may accommodate itself to the different positions of the lever 1 so that in effect it constitutes a sliding closure for the said opening. By this means moisture and dirt is effectively excluded from the outer end of opening 13 of the door 6 and from the elements of the lever and bracket assembly which are housed within said opening.

The bolt 12 is formed as best shown in Fig. 2. This element is generally cylindrical in form and has a pair of spaced cylindrical flanges 36 and 37, the latter flange being located at the inner end of the bolt and the flange 36 toward the other end. The flanges are dimensioned to fit neatly and slidably within the cylindrical bore 38 in the lever 1 in which the bolt is mounted. A pin 39 projects inwardly from the wall of the bore between the flanges 36 and 37 and by engagement with these flanges limits the movement of the bolt in the bore. A spring 41 in the bottom of the bore bears against the inner face of the flange 37 and tends to hold the bolt in the extended position in which it is shown in Fig. 2, this position being determined by the pin 39 which as shown engages the face of the flange 37. In this position the outer face of the flange 36 lies flush with the terminal end of the bore 38. The projecting end portion 42 of the bolt which extends outwardly beyond the flange 37 has an outer beveled edge 43, and the sides of this end portion of the bolt between the bevel and the outer face of the flange 36 are undercut, as illustrated, or, in other words, slant inwardly from the inner edge of the bevel surface 43 toward the pin axis.

The keeper 9 is formed as shown in Figs. 2 and 5 so as to coat with the bevel surface 43 of the bolt and the inclined side wall 44 to cause retraction of the bolt when the door is closing and, when the door is closed, to prevent such retraction of the bolt by pressure exerted directly on the screen. Thus the keeper 9 has at its outer side, i. e., that side which faces toward the door, an inclined surface 45 which when the door is moving towards closed position is engaged by the beveled face 43 so that a component force will press the bolt inwardly against pressure of the spring 41 to an extent such that the bolt may clear the outer end of the keeper. It will be noted also that just inwardly of the bore 38 at the base of the handle element 3 the lever 1 has a beveled surface 46 which is disposed also for engagement with the inclined surface 45 of the keeper as the door is closing so as to cam the lever about the pivot 5 to an extent permitting passage by the keeper of that portion of the lever.

As the door is closing, the surface 46 will first engage the surface 45 of the keeper to turn the lever 1 in the counterclockwise direction as viewed in Fig. 2, and subsequently when the surface 46 has cleared the end of the keeper the beveled end surface 43 of the bolt will contact the surface 45 to force the bolt 43 inwardly against the pressure of spring 41 to an extent permitting the outer end of the bolt to clear the keeper. Thereafter the lever 1 is returned to the normal position, as shown in Fig. 2, by action of the spring 23 and the bolt 43 is projected to the normal position by the spring 41 so that the parts assume positions with respect to the keeper as shown in Fig. 2. In this position, by reason in part of the inclination of the axis of the bolt to the plane of the door and in part by the under-

cut walls 44 of the projecting end of the bolt which, as shown in Fig. 1, is engaged by the tip end 55 of the keeper, the bolt and keeper will be so interengaged that pressure exerted directly on the door tending to open the latter will tend only to force the bolt outwardly, so that the latch is positively maintained in operative position. With reference to Fig. 9, it will be seen that the force F exerted by the keeper 9 on the inclined surface 44 of the bolt 12 has a component x along the longitudinal axis X—X of the bolt 12. The force F is normal to the surface 44 because of the relatively frictionless contact between said surface and the keeper 9. Only by movement of the lever as a whole, resulting either from an outward pull on the handle 2 or an inward pressure on the handle 3, can the terminal end of the bolt 12 be released from the keeper.

At the top of the bracket 4 is a cylinder 47 in which is slidably mounted a pin 48. A handle 49 attached to the pin 48 projects through a bayonet slot 51 in the wall of the cylinder 47, and a spring 52, see Fig. 7, in the bottom of the cylinder 47 tends to force the pin 48 upwardly in the cylinder. An inner reduced end 53 of the pin 48 extends through an opening in the bottom of cylinder 47 and the latter is so located that the end of the pin, when projected downwardly from the bottom of the cylinder will occupy a position as shown in Fig. 2 wherein it lies in close proximity to the side of the lever 1 to thereby prevent a pivotal movement of the lever releasing the bolt 12 from the keeper. The pin 48 may be moved downwardly against the base of the spring 52 by means of the handle 49, the handle 49 then being shifted transversely into the lower offset end of the bayonet slot 51 to retain the pin in the extended or lever-locking position.

This same pin may be used to retain the lever 40 in a retracted position in which the bolt 12 lies clear of the keeper so that the door is free from the latch. Thus, when the pin 53 is projected downwardly into the recess 54 in the upper side of the lever 1, as shown in Fig. 7, the projecting end of the pin will engage the side wall of the slide and hold the lever in the retracted position, as shown in Fig. 3, and in full lines in Fig. 1.

It will be apparent that the device is subject to modification in detail without departure from the invention.

I claim:

1. A door latch for engagement with a keeper on the door frame, said latch comprising a lever extending through the door from one side to the other and having a handle at each end, means for pivotally supporting said lever in the door, and a longitudinal bolt member slidably mounted in a guideway within the inner handle of the lever and extending therefrom in a position to engage the keeper and mounted for movement on a straight line converging at a substantial angle with the plane of the door in the direction of the keeper, the extended end of the bolt increasing in cross sectional area toward its outer end, whereby pressure of the keeper upon said diverging surface when the door is closed will act to maintain the bolt in extended locking position, said bolt effectively closing said guideway to the admittance of foreign matter, and resilient means tending to retain the bolt in the extended position.

2. A door latch for engagement with a keeper on the door frame, said latch comprising a lever extending through the door from one side to the other and having a handle at each end, means

for pivotally supporting said lever in the door, and a longitudinal bolt member slidably mounted in a guideway within the inner handle of the lever and comprising spaced flanges, one at the inner end and another at its midsection, said flanges seating neatly in and effectively eliminating transverse motion of the bolt within the guideway, said bolt effectively closing said guideway to the admittance of foreign matter, and extending therefrom in a position to engage the keeper, and resilient means tending to retain the bolt in the extended position.

3. A door latch according to claim 2 wherein a pin is mounted in the guideway between said flanges to serve as a stop limiting the longitudinal movement of the bolt within the guideway.

4. A door latch according to claim 3 wherein the resilient bolt-extending means consists of a spring seated in the guideway and bearing against one of said flanges.

5. In a door latch, a lever extending through the door from one side to the other and having a handle at each end, a bracket secured to the inner side of the door and to which the lever is pivotally connected for oscillation in a plane approximately normal to the plane of the door, a bolt element carried by the lever inwardly of the pivot and arranged for inner engagement with the keeper on the door frame, said bolt being releasable from the keeper by a retractive movement of the lever about its pivot, a pin slid-

ably mounted on the bracket, the axis of said pin being perpendicular to the plane of motion of the lever and displaced therefrom for projection into said plane of motion behind the lever to prevent the said retractive movement of the latter and also to front of the lever after the latter has been retracted to prevent return of the lever to the door latching position, and spring tending to retract the pin from engagement with the lever, and a handle element extending outwardly from said pin, said handle element projecting through a generally L-shaped aperture in the bracket and being movable transversely of the pin into the offset end of the aperture to thereby maintain the pin in lever-engaging position against the pressure of said spring.
